(57) **CLAIM**

The ornamental design for an upper frame for an off-road vehicle as shown and described.

DESCRIPTION

FIG. 1 is a front-left side perspective view of an upper frame for an off-road vehicle embodying our new design; FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The portions of the upper frame for the off-road vehicle shown in broken lines form no part of the claimed design.

1 Claim, 5 Drawing Sheets
